(57) **CLAIM**

The ornamental design for a personal protective shield for motorcycle rider, as shown and described.

DESCRIPTION

FIG. 1 is a perspective view of a personal protective shield for motorcycle rider, showing my new design,

FIG. 2 is an elevation view of the exterior thereof,

FIG. 3 is an elevation view of the side thereof; and,

FIG. 4 is an elevation view of the interior thereof.

The broken lines in the figures depict environmental subject matter that forms no part of the claimed design.

1 Claim, 3 Drawing Sheets
